UNITED STATES PATENT OFFICE.

JULIUS CAESAR, OF NEW YORK, N. Y.

DESIGN FOR A SIGN CHARACTER.

SPECIFICATION forming part of Design No. 31,262, dated July 18, 1899.

Application filed October 31, 1898. Serial No. 695,135. Term of patent 14 years.

To all whom it may concern:

Be it known that I, JULIUS CAESAR, a citizen of the United States, residing at New York, in the county of New York and State of New York, have invented and produced a new and original Design for Sign Characters, of which the following is a specification, reference being had to the accompanying drawings, forming part thereof, in which—

- o Figure 1 is a face view of the letter "E," illustrating my invention; and Fig. 2, a section on the line 2 2 of Fig. 1.

The leading or material feature of my design, as shown in the drawings, consists of 5 the configuration given to the character, which consists of a central colored portion 5, surrounded or inclosed on all sides by a border 6, of lighter color than the central portion, and at each of the angles or curves of the character are radial lines 7, which extend from the central colored portion across the border or lighter-colored portion in each direction.

In making signs, as is well known, the various letters of the alphabet, the numerals, and other characters are employed, and it will 25 be apparent that my design may be applied to all letters, numerals, or other characters in making signs.

Having fully described my invention, I claim as new and desire to secure by Letters 30 Patent—

The design for a sign character herein shown and described.

In testimony that I claim the foregoing as my invention I have signed my name, in presence of the subscribing witnesses, this 35 28th day of October, 1898.

JULIUS CAESAR.

Witnesses:

F. A. STEWART,
C. C. OLSEN.
